INSULATED BEVERAGE SERVER

Gene Martin, 616 Richmond Road, East Meadow,
Long Island, N.Y.

Filed Mar. 18, 1965, Ser. No. 84,343

Term of patent 7 years

(Cl. D44—21)

FIG. 2 is a rear perspective view thereof;

FIG. 3 is a top plan view thereof;

FIG. 4 is a side elevational view thereof; and

FIG. 5 is a rear elevational view thereof.

I claim:

The ornamental design for an insulated beverage server, substantially as shown.
